BRUSHCUTTER ATTACHMENT FOR CHAIN SAW ENGINE DRIVE

The present invention relates to portable power tools, and particularly to an attachment whereby a brushcutter mechanism may be adapted to utilize a wide variety of commercially available chain saw engines as a power source.

BACKGROUND OF THE INVENTION

The utility and commercial success of portable power tools may be greatly enhanced by adapting a tool, or a particular part thereof, to a widened variety of uses. The greater the number of tasks that may be performed by a particular tool, the greater the value and marketability thereof. Interchangeability between parts of different tools can contribute greatly to widening the practical uses of a tool thereby enhancing its value. For example, if a single power source, such as an internal combustion engine or an electric motor, there would result an improvement adapted to have attached thereto a variety of operating instrumentalities, e.g., drills, saws, sanding attachment, etc., thereby greatly expanding the utility of each individual part and providing a combined mechanism featuring high versatility and economy of cost.

However, a prime prerequisite of such interchangeability is simplicity. The attachment must be such that they can be quickly engaged by the user with facility and ease.

Accordingly, it is the object of the present invention to provide means whereby a brushcutter mechanism may be adapted to utilize a variety of chain saw engines as a driving mechanism.

The brushcutter mechanism intended for use in the preferred embodiment of the present invention is similar, in many important respects, to the device described in U.S. Pat. No. 2,397,457 to Benjamin F. Lawrence which is assigned to the same assignee as the present invention. The method of operation by a user described in the patent to Lawrence pertains to the present invention, which may be operated in a basically similar fashion. Also the brushcutter mechanism discussed herein, although differing in many essential respects from the Lawrence invention, nevertheless may be constructed to comprise similar structural details. The differences and similarities will be better understood in light of the description which follows.

SUMMARY OF THE INVENTION

Briefly, the present invention comprises an arrangement whereby a power tool, such as a brushcutter attachment having a brushcutter operating instrumentality attached to one end, may be adapted to be mounted upon and receive power from a commercially available chain saw engine.

More specifically, the end of the brushcutter attachment opposite the end comprising the operating instrumentality is mounted to be driven by a chain saw engine by removing from the chain saw engine the clutch drum and chain bar, and replacing these members with a substitute clutch drum according to the present invention which, together with power transmission stud means, is adapted to transmit power to the drive shaft of the brushcutter attachment which is mounted upon the chain saw engine.

BRIEF DESCRIPTION OF THE DRAWING

A better understanding of the invention may be had by reference to the following detailed description of a preferred embodiment thereof taken in connection with the accompanying drawings wherein:

FIG. 1 is an isometric fragmented view showing the individual parts of the present invention together with parts of a chain saw in dotted form;

FIG. 2 is a more detailed isometric view illustrating the mounting of the brushcutter attachment to the chain saw engine; and

FIG. 3 is an isometric view of the assembled embodiment described herein with the brushcutter attachment mounted to the chain saw engine and in position to receive driving power therefrom.

DESCRIPTION OF THE PREFERRED EMBODIMENT

The drawing depicts a chain saw internal combustion engine 10 shown in dotted form and shaped simply as a rectangular box. Since the present invention is intended for use with a variety of chain saw engines, and since the particular shape and configuration of chain saw engines can vary and would form no part of the present invention, except as will hereinafter be described, it is considered appropriate for simplicity of description and understanding to depict the chain saw engine 10 as indicated. Other parts of the chain saw which must be removed therefrom prior to attachment of the elements forming the present invention are shown in dotted form in FIG. 1. These parts are the chain bar 12 and the clutch drum 14.

The parts of the chain saw engine 10 which are important for purposes of the present invention are the centrifugal clutch 16 and the mounting studs 18 and 20. The centrifugal clutch 16 is of a type well known in the art and well within the knowledge of anyone of ordinary skill in the art. The clutch 16 comprises a pair of shoes 22 and 24 mounted about an engine drive shaft 26. When the engine 10 increases in speed, the shoes 22, 24, are forced radially outwardly by centrifugal force away from drive shaft 26 and against the biasing force of spring means (not shown).

The clutch drum 14 includes a sprocket means 15 and in the normal operation of the engine 10 as a chain saw drive means, the clutch drum 14 is mounted and locked upon drive shaft 26 by means of nut 28 and flatwasher 30. With the clutch drum 14 mounted upon drive shaft 26, the inner surface of the clutch drum is adapted to be frictionally engaged and rotatively driven by shoes 22 and 24 when the appropriate speed is reached. The chain bar 12 at its mounted end 13 is adapted to have the chain 47 engage the sprocket means 15 thereby driving the chain 47 during cutting operations.

The chain bar 12 is also mounted upon the face of the engine over drive shaft 26 and is locked in place and supported upon studs 18 and 20 by nuts 32, 34 and flatwashers 36, 38. It should be noted that in utilizing the elements of the present invention as will hereinafter be described the same nuts 28, 32 and 34, and flatwashers 30, 36 and 38, as are supplied with the chain saw may be used.

When it is desired to convert the unit from a chain saw to a brushcutter, it is necessary to merely loosen nuts 28, 32 and 34 and remove the chain bar 12 and the clutch drum 14 and subsequently mount upon the engine 10, in accordance with the present invention, a substitute clutch drum 40 and a power tool such as a brushcutter attachment generally labelled 50, in a manner to be described hereinafter.

The substitute clutch drum 40 is mounted upon drive shaft 26 and is driven by centrifugal clutch 16 in a manner similar to that involving clutch drum 14. The basic difference between clutch drum 14 and substitute clutch drum 40 is that substitute clutch drum 40 does not utilize a sprocket means to transmit power, but rather comprises a plurality of orifices 42 which may be engaged by mating studs. However, the inner surface of substitute clutch drum 40 is adapted to be frictionally engaged by shoes 22, 24 in a manner similar to the operation of clutch drum 14 previously described, and after replacement of clutch drum 14 by substitute clutch drum 40 upon drive shaft 26, and locking thereon by replacement of nut 28 and flatwasher 30, the substitute clutch drum 40 will be in place to receive power when the speed of engine 10 reaches an appropriate level.

The brushcutter attachment 50 comprises an elongated tubular member 52 whose cutting end has mounted thereon a housing 54 containing gear means therein for transmitting power from a drive shaft 56 mounted within member 52 to an

operating instrumentality such as a circular saw 58. The housing 54 may have mounted therein any appropriate gear arrangement whereby power is transmitted from shaft 56 to saw 58. The particular gear arrangement utilized will be within the ordinary mechanical skill of someone having ordinary knowledge in the art, and forms no part of the present invention. One gear arrangement which may be utilized is described in the aforementioned patent to Lawrence.

The shaft 56 is rotatably mounted within member 52 by appropriate bearing means (not shown) and terminates at the end thereof opposite saw 58 within a clutch housing 60. The bearing means utilized and the method of mounting shaft 56 within member 52 may likewise be similar to the arrangement described in the Lawrence patent. A plate 62 having studs 64 fixedly mounted thereon is rotatably situated within housing 60, with the plate 62 being affixed to shaft 56 by any suitable means, e.g., by being integrally formed therewith or by a slot and key arrangement (not shown).

The housing 60 has integrally formed thereon a mounting plate 66 comprising orifices 68 and 70 which are adapted to have studs 18 and 20 extend therethrough.

When mounting the brushcutter attachment 50 onto the chain saw engine 10, the studs 64 are inserted into orifices 42 in substitute clutch drum 40 which has been previously mounted onto drive shaft 26 and locked in place by nut 28 and washer 30. The orifices 68 and 70 will be aligned with and mounted upon studs 18 and 20 respectively, with the threaded ends 19 and 21 extending a sufficient distance beyond the surface of plate 66 to permit engagement thereof by nuts 32 and 34. With the elements in place, the flatwashers 36 and 38, and the nuts 32 and 34 may be appropriately mounted upon studs 18 and 20 with the nuts being tightened to secure the entire assembly.

The attachment 50 comprises a pair of handles 72 and 74 mounted onto member 52 which a user may grip, one in each hand, in a manner similar to that described in the Lawrence patent, when operating the device. A throttle control lever 76 is mounted on handle 74 with a throttle cable 78 extending to engine 10 and attached thereto, in a manner well known in the art, to control the speed at which the engine is operated. Thus, a user may control the speed of rotation of the engine drive shaft 26, and consequently the operating speed of the saw 58, merely by manipulation of lever 76.

It will be apparent that in the operation of the invention, power is transmitted to drive shaft 26 and when the appropriate rotational speed is reached, the shoes 22, 24 are driven by centrifugal force radially outwardly and into frictional engagement with clutch drum 40 which is thereby caused to rotate. With studs 64 engaging the clutch drum 40 in orifices 42, rotation of drum 40 is imparted to the operating instrumentality or saw 58 through shaft 56 and the gear mechanism contained in housing 54.

It will be found that most chain saw engines are identical in many of the dimensions with which the present invention is concerned. Although there may be some variation, it will be seen that the brushcutter attachment 50 and the clutch drum 40 may be readily and economically adapted to these variances. For example, most lightweight chain saw engines are identical in respect to the distance from the center of the drive shaft 26 to the mounting studs 18, 20, as well as the center distance between mounting studs. Although there is a good deal of standardization in the manufacture of chain saws, some variations may be found to exist, such as a difference in drive shaft diameter or in mounting stud diameter, between one manufacturer and another. Such variances, however, may be easily provided for by knowing the name of the particular manufacturer of the chain saw with which the brushcutter attachment is to be used, and specifically providing dimensions, e.g., clutch drum diameter, to operate with the chain saw engine intended. Thus, a specific size clutch drum 40 may be provided with a particular unit, or a single brushcutter attachment 50 or other similar power tool may be adapted for operation with an expanded number of chain saw engines

merely by providing substitute clutch drums of various sizes with each unit.

It will be apparent from the foregoing that the present invention provides a power tool arrangement of great versatility and expanded effectiveness, and one which permits the utilization of a readily available power source to a significantly broader range of usage thereby greatly enhancing its value. It should be particularly noted that the changeover from chain saw to brushcutter can be effected in a manner featuring great simplicity and ease of accomplishment, merely by the removal of three nuts, i.e., nuts 28, 32 and 34, and the replacement of two parts, i.e., clutch drum 14 and chain bar 12, by two other parts, i.e., clutch drum 40 and brushcutter attachment 50. Further, replacement of parts is at a minimum since only a substitute clutch drum 40 and a brushcutter attachment 50 need be provided with the commonly available chain saw.

I claim:

1. A power tool arrangement comprising a power source including a drive shaft, driving clutch means receiving power from said drive shaft, driven clutch means adapted to engage said driving clutch means, power transmission means, stud means interposed in engaging relationship between said power transmission means and said driven clutch means to transmit power therebetween, a power tool including a power tool operating instrumentality, and means transmitting operative power from said power transmission member to said operating instrumentality.

2. A power tool arrangement according to claim 1 wherein said power tool comprises a brushcutter attachment consisting essentially of a hollow elongated tubular member having a brushcutter attachment drive shaft rotatively mounted therein, said power transmission means being fixedly mounted to one end of said brushcutter attachment drive shaft, with said stud means, said power source drive shaft and said brushcutter attachment drive shaft all in parallel relationship.

3. A power tool arrangement according to claim 1 wherein said driven clutch means defines stud engaging orifice means said power transmission member means having said stud means mounted thereon in mating relationship with said stud engaging orifice means for effecting power transmission between said driven clutch means and said power transmission means.

4. A power tool arrangement according to claim 1 wherein said stud means are integrally formed upon said power transmission means and are circumferentially spaced about the axis of rotation of said power source drive shaft to rotate thereabout in a circular path.

5. A power tool arrangement according to claim 2 including a housing member integrally formed upon said hollow elongated tubular member, said housing member enclosing said driven clutch means and said power transmission means and having formed integrally therewith a mounting plate defining orifice means engaging said power source to effect mounting of said brushcutter attachment thereon.

6. A power tool arrangement according to claim 5 wherein said power source is a chain saw engine which includes a plurality of mounting studs said mounting plate orifice means being aligned to engage said chain saw mounting studs, and being at least as great in number as said chain saw mounting studs.

7. A power tool arrangement according to claim 6 wherein said power source drive shaft, said brushcutter attachment drive shaft, said stud means and said chain saw mounting studs are parallel, with said mounting plate orifice means and said stud means being relatively spaced to simultaneously engage, respectively, said chain saw mounting studs and said stud engaging orifice means.

8. A power tool arrangement according to claim 7 comprising a conically shaped extension integrally formed upon said hollow elongated tubular member, a rectangularly shaped extension integrally formed upon said conically shaped extension, orifice means defined by said rectangularly shaped extension and aligned to engage said chain saw mounting studs

thereby to mount said brushcutter attachment upon said chain saw engine with said stud means aligned for engagement with said stud engaging orifice means.

9. A power tool arrangement according to claim 8 wherein said conically shaped extension encloses said driving clutch means, said driven clutch means and said stud means.

10. A power tool arrangement according to claim 2 wherein said power source drive shaft, said driving clutch means, said driven clutch means, said stud means and said brushcutter attachment drive shaft are all concentrically arranged to rotate about the same axis.
